[57] CLAIM

The ornamental design for the structural strut joint, as shown.

DESCRIPTION

FIG. 1 is a perspective view of a structural strut joint which has been sectioned through one quadrant thereof showing my new design;

FIG. 2 shows a midline sectional view of the outer portion of the structural strut joint with the inner portion having a partially fragmented midline sectioned view in the upper portion thereof; and,

FIG. 3 shows an upright elevation view of the entire structural strut joint.

FIG. 1

FIG. 2

FIG. 3
